The ornamental design for a nose piece for a folded sheet product dispenser, as shown and described.

DESCRIPTION

FIG. 1 is a front elevational view of a nose piece for a folded sheet product dispenser showing our new design; FIG. 2 is a top plan view thereof;

FIG. 3 is a right side elevational view thereof, the left side being a mirror image of that shown;

FIG. 4 is a bottom plan view thereof;

FIG. 5 is a rear elevational view thereof;

FIG. 6 is a horizontal cross-sectional view thereof, taken along line 6—6 of FIG. 1; and,

FIG. 7 is a vertical cross-sectional view thereof, taken along line 7—7 of FIG. 1.

FIG. 2

FIG. 1

FIG. 3

FIG. 7

FIG. 4

FIG. 5

FIG. 6
